UNITED STATES PATENT OFFICE.

WILLIAM F. CLAUD, OF PORTSMOUTH, VIRGINIA.

SAFETY DEVICE FOR SHIPS.

1,145,749.

Specification of Letters Patent. Patented July 6, 1915.

Application filed November 4, 1914. Serial No. 870,286.

To all whom it may concern:

Be it known that I, WILLIAM F. CLAUD, a citizen of the United States of America, residing at Portsmouth, in the county of 5 Norfolk and State of Virginia, have invented new and useful Improvements in Safety Devices for Ships, of which the following is a specification.

This invention relates to improvements in 10 safety devices or protectors for ships and other water craft and has particular application to a bow carried protector.

In carrying out the present invention, it 15 is my purpose to provide a safety device for ships which will be carried by the bow of the vessel and whereby the vessel will be enabled to glide off of the side of another vessel in the event of a collision and whereby the shock due to the impact between the ves- 20 sels will be largely absorbed or taken up.

It is also my purpose to provide a device of the class described whereby the passengers on the ship will be automatically advised when the impact takes place.

25 A further object of my invention is the provision of a safety device for water craft which will embrace the desired features of simplicity, efficiency and durability, which may be installed and maintained at a com- 30 paratively small expense and whereby the staving in of the side of the ship struck and the mutilation of the bow of the ramming ship will be avoided.

With the above and other objects in view, 35 the invention consists in the construction, combination and arrangement of parts hereinafter set forth in and falling within the scope of the claims.

In the accompanying drawings; Figure 1 40 is a fragmentary side elevation of a ship equipped with a safety device constructed in accordance with the present invention. Fig. 2 is a fragmentary top plan view of a ship equipped with my improved safety device 45 ramming a second ship. Fig. 3 is an enlarged horizontal sectional view through the forepart of the ship showing the relative positions of the various parts of the safety device. Fig. 4 is a sectional view on the line 50 4—4 of Fig. 3. Fig. 5 is a similar view on the line 5—5 of Fig. 3. Fig. 6 is a like view on the line 6—6 of Fig. 3.

Referring now to the drawings in detail, A designates the bow of a ship. Formed in the side walls of the bow of the ship at opposite sides of the longitudinal center line thereof are pairs of openings 1, the openings of each pair being disposed one above the other and alining with the openings of the other pair. Passed through the pairs of 55 openings 1 are horizontal shafts 2 disposed one above the other and secured to the outer extremities of the shafts 2 is a substantially V-shaped frame 3 having the apex thereof in alinement with the longitudinal center 60 line of the vessel and the side walls spaced apart from the respective side walls of the bow of the vessel. Secured to the top and bottom edges of the frame 3 at the apex thereof are vertically alining bearings 4 and 65 journaled in these bearings is a vertical shaft 5 carrying a metal roller 6 provided with a covering of rubber 7 or analogous material, and formed on the top and bottom edges of the frame 3 and projecting out- 70 wardly therefrom at the extremities thereof are vertically alining bearings 8 in which are journaled vertical shafts 9 carrying metal rollers 10 covered with rubber 11. Disposed within each opening 1 and sur- 75 rounding the shaft therein is a boxing 12 provided with rollers 13 disposed at the opposite sides of the shaft and designed to permit the latter to move inwardly freely when the rollers on the frame 3 impact 80 against another vessel.

The shafts 2 are preferably disposed in a plane between two decks of the vessel and the inner ends of such shafts pass through a transverse bar 14 extending across the bow 90 of the vessel between the floor of one deck and the ceiling of the next lower deck and having the ends thereof suitably secured to the side walls of the vessel. This bar 14 is preferably reinforced through the medium 95 of brace bars 15. Encircling the shafts 2 upon the front side of the brace bar 14 are compression springs 16 having the inner ends thereof abutting the bar 14 and the outer extremities engaging the end portions 100 of a plate 17 spanning the space between the pairs of shafts and fixed to the latter, while encircling the shafts 2 behind the bar 14 are coiled retractile springs 18 having the outer

ends thereof suitably secured to the bar 14 and the remaining ends appropriately fastened to the extremities of the respective shafts 2.

- 5 In the present instance, horizontal rods 19 corresponding in number with the shafts 2 are passed through the side walls of the bow of the ship and have the outer ends thereof secured to the inner side of the frame 3 and 10 the inner extremities fastened to the plate 17, the rods 19 coating with the shafts 2 to reinforce the structure of the safety device.

In practice, should a vessel equipped with my improved safety device ram a second vessel, the bow of the first vessel striking the side of the second vessel, as illustrated in Fig. 2 of the drawings, the shafts 2 and rods 19 will move inwardly and in the inward movement of the rods the compression springs 16 will be compressed while the retractile springs 18 will be expanded, thereby absorbing the shock due to the impact between the vessels and enabling the ramming vessel to be swung around so that such vessel will glide off of the rammed ship, the rollers enabling the ramming vessel to glide off of the side of the other vessel. As the rollers ride over the side of the struck vessel, the rubber covering on such rollers eliminates friction and so enables the particular vessel to glide away from the struck ship easily and noiselessly, the springs 16 and 18 reacting and restoring the frame 3 to normal position when the pressure on such frame is removed.

In order that the passengers of the ship may be warned when the frame 3 moves inwardly under the impact, a circuit closer 20 is disposed in the path of movement of a lug 21 on one of the rods 19 and this circuit closer controls an electric circuit 22 including a suitable source of electrical energy and signals located in the respective staterooms on the vessel, a visual signal and an audible signal being preferably located in each stateroom of the vessel. Thus, when the circuit 22 is closed, the signals in the staterooms are energized and the occupants of such rooms notified that the vessel has struck a second vessel or other object.

Cords 23 and 24 are preferably connected with the circuit closer 20 and extend into the pilot house of the ship and by means of these cords 23 and 24 the circuit closer 55 may be opened and closed by the pilot of the vessel whenever necessary. Thus, should the side of the ship be struck by the bow of another vessel the pilot of the rammed vessel 60 may notify the passengers of the impending danger by pulling the cord 24 and closing the circuit closer whereby the circuit will be closed and the signals energized.

From the foregoing description taken in

connection with the accompanying drawings, the construction and mode of operation 65 of my improved safety device will be readily apparent.

It will be seen that I have provided a safety device for vessels whereby the shock due to the bow of one vessel striking against 70 the side of another vessel will be cushioned and the striking vessel enabled to glide off of the side of the vessel struck without staving in the side and bow of the respective vessels.

While I have herein shown and described one preferred form of my invention by way of illustration, I wish it to be understood that I do not limit or confine myself to the precise details of construction herein described and delineated, as modification and variation may be made within the scope of the claims without departing from the spirit of the invention.

I claim:

1. In a device of the class described, the combination with the bow of a ship having pairs of openings formed in the side walls thereof, boxings within said openings, shafts passed through said boxings, rollers journaled in said boxings and disposed at the opposite sides of the respective shafts, a V-shaped frame secured to the outer ends of said shafts, rollers journaled in the outer surfaces of said frame and adapted to impact against the side of a ship in the event of a collision, a bar arranged transversely of the bow of the ship and formed with openings through which said shafts pass, a plate fixed to said shafts in advance of said bar, compression springs surrounding said shafts between said bar and plate, and retractile springs surrounding said shafts between said bar and the inner ends of the shafts and each having one end fastened to the bar and the remaining end secured to the shaft.

2. In a device of the class described, the combination with the bow of a ship having pairs of openings formed in the side walls thereof, boxings within said openings, shafts passed through said boxings, rollers journaled in said boxings and disposed at the opposite sides of the respective shafts, a V-shaped frame secured to the outer ends of said shafts, rollers journaled in the outer surfaces of said frame and adapted to impact against the side of a ship in the event of a collision, a bar arranged transversely of the bow of the ship and formed with openings through which said shafts pass, a plate fixed to said shafts in advance of said bar, compression springs surrounding said shafts between said bar and plate, retractile springs surrounding said shafts between said bar and the inner ends of the shafts and

each having one end fastened to the bar and the remaining end secured to the shaft, and horizontal rods passed through the bow of the ship and having the outer ends secured 5 to the inner surfaces of said frame and the inner extremities fast to said plate.

In testimony whereof I affix my signature in presence of two witnesses.

WILLIAM F. CLAUD.
